(57) **CLAIM**

The ornamental design for a printer, as shown and described.

DESCRIPTION

The patent or application file contains at least one drawing executed in color. Copies of this patent or patent application publication with color drawing(s) will be provided by the office upon request and payment of the necessary fee.

FIG. 1 is a perspective view of a printer showing my new design in a closed state;

FIG. 2 is second perspective view thereof;

FIG. 3 is a front elevational view thereof;

FIG. 4 is a rear elevational view thereof;

FIG. 5 is a left elevational view thereof;

FIG. 6 is a right elevational view thereof;

FIG. 7 is a top plan view thereof; and

FIG. 8 is a bottom plan view thereof;

FIG. 9 is a perspective view of a printer showing my new design in an open state;

FIG. 10 is second perspective view thereof;

FIG. 11 is third perspective view thereof;

FIG. 12 is a front elevational view thereof;

FIG. 13 is a rear elevational view thereof;

FIG. 14 is a left elevational view thereof;

FIG. 15 is a right elevational view thereof; and,

FIG. 16 is a top plan view of the bottom part thereof.

The broken lines depict portions of the printer that form no part of the claimed design. In addition, the unshaded surface that directly adjoins the claimed edge in FIG. 17 forms no part of the claimed design.

1 Claim, 16 Drawing Sheets
